Primary Examiner — Karen S Acker*Assistant Examiner* — Jasmine Mlinarcik(74) *Attorney, Agent, or Firm* — McCoy Russell LLP(57) **CLAIM**

The ornamental design for a field cap, as shown and described.

DESCRIPTION

FIG. 1 is a front-right perspective view of a design for a field cap according to the present invention.

FIG. 2 is a top plan view thereof.

FIG. 3 is a front elevation view thereof.

FIG. 4 is a rear elevation view thereof.

FIG. 5 is a rear-right perspective view thereof.

FIG. 6 is right side elevation view thereof.

FIG. 7 is a left side elevation view thereof; and,

FIG. 8 is a bottom plan view thereof.

The broken lines in FIGS. 1-8 illustrate environmental stitching and form no part of the claimed design.

1 Claim, 8 Drawing Sheets(56)
